DESIGN FOR AN ENSEMBLE DRESS

Harry Schwartz, New York, N. Y., assignor to Franklin Simon & Co., Inc., New York, N. Y.

Application February 1, 1935, Serial No. 55,199

Term of patent 3½ years

To all whom it may concern:

Be it known that I, Harry Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

I claim:

The ornamental design for an ensemble dress, substantially as shown.

HARRY SCHWARTZ.
